CLAIM

The ornamental design for a back scratcher as shown and described.

DESCRIPTION

FIG. 1 is a front, left and bottom perspective view of a back scratcher showing my design;

FIG. 2 is a rear, right and top perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is an enlarged top plan view of the back scratcher; and,

FIG. 8 is an enlarged bottom plan view of the back scratcher. The broken lines shown in the drawings depict portions of the back scratcher that form no part of the claimed design.

1 Claim, 8 Drawing Sheets
